[57] CLAIM

The ornamental design for a combination yarn holder and dispenser, as shown and described.

DESCRIPTION

FIG. 1 is a top plan view of a combination yarn holder and dispenser showing my new design;

FIG. 2 is a right side elevational view thereof;

FIG. 3 is a front elevational view thereof;

FIG. 4 is a bottom plan view thereof;

FIG. 5 is a cross-sectional view taken along line 5—5 of

FIG. 1; and

FIG. 6 is a rear elevational view thereof.
